UNITED STATES PATENT OFFICE.

FRANCIS V. DONNELLY, OF GREENSBURG, PENNSYLVANIA.

CURTAIN-POLE.

No. 900,497.

Specification of Letters Patent.

Patented Oct. 6, 1908.

Application filed April 30, 1908. Serial No. 430,195.

To all whom it may concern:

Be it known that I, FRANCIS V. DONNELLY, a citizen of the United States of America, residing at Greensburg, in the county of 5 Westmoreland and State of Pennsylvania, have invented certain new and useful Improvements in Curtain-Poles, of which the following is a specification, reference being had therein to the accompanying drawing.

10 This invention relates to a curtain pole, and the objects of my invention are, first, to provide a novel pole to which curtains can be attached without the use of rings or pins; second, to provide a novel telescopic pole that can be adjusted to fit window-frames of various widths; third, to provide novel brackets for supporting my poles; and fourth, to provide a simple, durable and comparatively inexpensive pole.

20 I attain the above objects by a pole that will be presently described and then specifically pointed out in the appended claims.

Referring to the drawings forming a part of this specification, Figure 1 is an elevation 25 of my pole partly broken away, Fig. 2 is a plan of the same, Fig. 3 is an enlarged cross sectional view of the pole in a closed position, and Fig. 4 is a similar view of the pole in an open position.

30 In the accompanying drawings, 1 designates a portion of a window-frame or a suitable support to which is secured by suitable means, as screws or nails 2, curved plates 3, of wood or metal, the curved portion of 35 each plate being provided with vertically alining openings 4. Adapted to fit in the openings 4 of said plates are depending ends 5 of brackets employed for supporting my pole, each bracket being constructed of a 40 piece of strong and durable wire or metal bent to provide a permanent support 6 and a temporary support 7 for the pole. The wire or metal of each bracket is bent to provide a curved guide 8 and a hook-shaped 45 support 9, said curved guides having clips 10 secured to their outer faces, the object of which will presently appear.

The curtain pole is formed of any desirable light and durable material, preferably 50 metal, and consists of two members, one of said members being soldered or fixed to the supports 6 and 9 of each bracket, while the other of said members is connected to the stationary member and is adapted to be 55 guided by the guides 8 when moved to the temporary supports 7 of the brackets.

The stationary member comprises two semi-cylindrical shells 11 and 12, the former having its longitudinal edges flanged as at 13 to receive the latter. The outer ends of 60 the shells 11 and 12 are closed by plates 14, provided with inwardly projecting pins 15 and with outwardly projecting ornamentations 16.

The movable member of the curtain pole 65 comprises shells 17 and 18 connected together similar to the shells 11 and 12 of the stationary member, said shells 17 and 18 having their outer ends closed by plates 19 provided with notches 20 to receive the pins 70 15 of the plates 14 of the stationary member, which can be either attached to the movable or stationary shells. The ends of the shells 11 and 17 are connected together by a tension helico-volute spring 21, while the 75 shells 12 and 18 have their outer ends connected by a similar spring, these springs maintaining the two members together to provide a cylindrical metallic pole.

The movable member of the curtain pole 80 is provided with straps 22, these straps being located adjacent to the ends of said member and embracing the guides 8 of the brackets, whereby when said member is moved, it will be guided to the temporary 85 support 7 and retained upon said support by the straps 22 engaging under the clips 10 of the brackets. The movable member in an open position is best shown in Fig. 4 of the drawings, and when in this position, the 90 upper ends of curtains 23 can be easily placed in engagement with the stationary member, and then the movable member released to assume its normal position and frictionally hold the curtains 23. It is obvious that the 95 curtains can be suitably arranged, or draped from the pole.

By providing the telescopic shells for the two semi-cylindrical members of my pole, the pole can be lengthened or shortened for 100 use in connection with windows or doorways of various widths, and when the pole is made of metal it can be finished to present a neat and attractive appearance.

The invention as above described is susceptible to such structural changes as are 105 permissible by the appended claims.

Having now described my invention what I claim as new, is:—

1. The combination of brackets, each 110 bracket comprising a permanent support, a temporary support, a guide and a hook-

- shaped support, a stationary semi-cylindrical member carried by said permanent and said hook-shaped supports; said member comprising telescopic shells, plates closing the outer 5 ends of said shells, a movable member slidably connected to said guides and adapted to be moved to said temporary supports, said movable member comprising telescopic shells, springs connecting the shells of said 10 movable member to the shells of said stationary member, and means carried by said guides for holding said movable member upon said temporary supports.
2. The combination with brackets, of a 15 stationary member carried thereby, a movable member connected to said brackets and adapted to normally engage said stationary member, said members comprising telescopic shells, springs for holding said movable

member in engagement with said stationary member, and means carried by said brackets for holding said movable member in an open position.

3. A curtain pole embodying a stationary member, a movable member, said members comprising telescopic semi-cylindrical shells, plates closing the outer ends of said members, and springs arranged between said members for normally holding said movable member in engagement with said stationary member, substantially as described.

In testimony whereof I affix my signature in the presence of two witnesses.

FRANCIS V. DONNELLY.
